UNITED STATES PATENT OFFICE.

AUGUST J. LUNDBERG, OF NEW YORK, N. Y., ASSIGNOR TO AUGUST J. LUNDBERG, EDWARD M. DAVIDSON, AND MAURICE DAVIDSON, DOING BUSINESS AS PAC-RITE COMPANY, OF NEW YORK, N. Y.

FOLDING FORM FOR GARMENTS.

1,044,462.

Specification of Letters Patent.

Patented Nov. 12, 1912.

Application filed October 14, 1911, Serial No. 654,607. Renewed June 5, 1912. Serial No. 701,912.

To all whom it may concern:

Be it known that I, AUGUST J. LUNDBERG, a citizen of the United States, and a resident of the city, county, and State of New York, 5 have invented a new and useful Improvement in Folding Forms for Garments, of which the following is a specification.

The object of my invention is to provide a suitable form which may be used with a 10 coat when folded or packed, so that the garment will be held without creasing and in its proper lines. This object is accomplished by my invention, one embodiment of which is hereinafter set forth.

15 For a more particular description of my invention, reference is to be had to the accompanying drawings, forming a part hereof, in which—

Figure 1 shows a blank form from which 20 my improved form is made. Fig. 2 shows a form ready for use. Fig. 3 shows a coat applied to the form. Fig. 4 shows a coat folded on a form.

Throughout the various views of the 25 drawings, similar reference characters designate similar parts.

The blank 1 is made of card board or suitable material having a body portion 2 with curved sides 3 and 4 and a collar 5 30 provided with a tongue 6 and slot 7. The blank may be provided with a perforation 8 in the collar and also with perforations 9 and 10 near the bottom of the body portion 2 formed in tabs 11 and 12. A medial 35 crease 13 may also be formed in the body portion 2 which extends from the collar 5 to the bottom to assist in folding the form.

When the tailor desires to use the form 40 he first engages the tongue 6 of the collar 5 in the slot 7, as shown in Fig. 2. He then takes a coat to which the form is to be applied and folds the sleeves and raises the collar in the usual manner, placing the facings of the coat over the sleeves, and then 45 inserting the form so that the collar of the form is against the collar of the coat and the facings of the coat are over the body portion with the form between the sleeves and the facings, or between parts of the 50 sleeves and facings, the sleeves being folded back on the form, as shown in Fig. 3. The

tabs 11 and 12 may then be placed on the exposed part of the facings, pins passed through the fabric of the coat through the perforations 9 and 10. A pin may also be 55 inserted at the collar 5 through the perforation 8. These pins, when inserted, rest against the form and do not perforate or mar the same, so that the form can be used a great number of times. The form and 60 garment may then be folded on the creased line 11, as shown in Fig. 4, and placed in the package for shipment.

While I have shown and described one embodiment of my invention, it is obvious 65 that it is not restricted to the exact details of construction shown and described, some of which may be omitted or changed, and it is intended that the invention shall be understood to cover all structures that come 70 within the scope of the annexed claims.

What I claim is:

1. In a garment form, a perforated collar and means for connecting the ends of the collar, and a perforated body portion with 75 curved sides connected to the collar, so that when the form is in use, portions of the fabric may be passed through said perforations and secured to the form.

2. In a garment form, a perforated collar 80 and means for connecting the ends of the collar, and a perforated body portion with tabs and curved sides connected to the collar, so that when the form is in use, portions 85 of the fabric of a garment may be passed through said perforations and secured to the form.

3. A garment form, comprising a perforated collar permitting a portion of the fabric to be passed through said perforation 90 and secured to the form, said collar being adapted to be curved or formed to correspond to the shape of the collar of the garment and provided with means for connecting the ends thereof together, and a flat 95 body portion having curved sides extending downwardly from said collar.

AUGUST J. LUNDBERG.
